United States Patent Office.

N. E. SMITH, OF EAST CLEVELAND, OHIO.

Letters Patent No. 66,261, dated July 2, 1867.

IMPROVEMENT IN SPLICING BELTING.

The Schedule referred to in these Letters Patent and making part of the same.

TO ALL WHOM IT MAY CONCERN:

Be it known that I, N. E. SMITH, of East Cleveland, in the county of Cuyahoga, and State of Ohio, have invented certain new and useful Improvements in Splicing Belts; and I do hereby declare that the following is a full and complete description of the same, reference being had to the accompanying drawings, making a part of this specification, in which—

Figure 1 is a view of two sections of belting cut for splicing.

Figure 2 a view of the sections when spliced.

Like letters of reference refer to like parts in the views presented.

The usual manner of splicing belts is by shingling or shaving down the hair side of one end of a piece of belting, and the flesh side of the other, and then lapping the two pieces upon each other and cementing them together with any appropriate material. To give additional strength and security to the splice of the larger class of belts rivets are employed, thus adding to the labor of making the belt and increasing the cost of the same. The objection to belts thus made is that the thin edges of the lap will break loose and curl up. This not only weakens the belt, but the folding back of the loosened ends forms ridges across the belt, thereby making it rough and uneven. Also belts made by thus splicing them are not so strong, for the reason of cutting away too much of the thickness of the leather. The stretching of the outer side of the belt, and consequent crimping of the inner side, as it bends in passing around the pulley, tend greatly to strain the lap apart by the opposite and unlike action exerted upon the splice. More especially is this the case when the belt passes around a small pulley, thus bringing the strain more across the grain of the leather, or rather the angle of the splice.

In order to avoid this difficulty, and give greater strength and security to the splice, the following-described way is adopted, viz:

The ends of the strips of belting B C, instead of being shaven down to long tapering wedge-like ends for the splice, are cut out vertically into a number of tapering tongues, A, fig. 1, thus preserving the thickness of the leather intact. The ends on being thus prepared are then glued and brought together and the tongues made to interlock, as shown in fig. 2. By this it will be evident that there is no weakening of the belt by shaving down the ends for the lap, which ordinarily requires about one-half the thickness of the leather; whereas in tonguing the splice in the manner as described, the whole thickness of the leather is retained; also in this splice, on bending or warping the belt around a pulley, there are no thin ends to break loose and roll up across the belt, making it rough and ridgy. In this manner of splicing the strain of the belt is with the grain of the leather, hence there will be no strain across the angle of the splice, nor any tendency to break apart, as in the old manner of splicing.

What I claim as my invention, and desire to secure by Letters Patent, is—

The herein-described method of splicing belts in the manner substantially as specified.

N. E. SMITH.
